GOLF BALL PUTTING GAME TARGET

John Joseph O'Shea, Cloneeven, Dublin Road,
Sutton, Ireland

Filed Apr. 29, 1974, Ser. No. 465,277

Term of patent 3½ years

Int. Cl. D21—01

U.S. Cl. D34—5 NN

FIG. 1

FIG. 2

FIG. 3

FIG. 4

FIG. 5

FIG. 6

FIG. 1 is a top perspective view of a golf ball putting game target showing my new design;

FIG. 2 is an end elevational view thereof;

FIG. 3 is a top plan view thereof;

FIG. 4 is a bottom plan view thereof;

FIG. 5 is a rear elevational view thereof; and

FIG. 6 is a view similar to FIG. 3 but showing a modification thereof.

I claim:

The ornamental design for a golf ball putting game target, as shown.
